CASTING MACHINE

August L. Weyhing, Louisville, Ky., assignor to
Edmund A. Steinbock, Louisville, Ky.

Application August 2, 1940, Serial No. 349,666

10 Claims. (Cl. 22—69.1)

This invention relates to improvements in a casting machine for casting metallic objects particularly such castings as are made for dental replacements.

It is one of the principal objects of this invention to provide a casting machine wherein the parts which support and cover the mold readily assume their proper alignment with respect to the mold prior to the application of pressure for forcing the molten metal into the mold and its crevices.

Another object of this invention is the provision, in a casting machine, of a mold support that has substantially universal movement for properly aligning the mold with the pressure plate of the casting machine to insure proper seal at the top of the mold by the pressure plate during the casting operation.

A further object of this invention is the provision in a casting machine accomplishing the foregoing object of means utilizing the movement of the mold support for opening the pressure control valve.

A still further object of this invention is the provision in a casting machine of a pressure plate mounted for substantially universal movement with respect to the mold for insuring proper seal by the pressure plate on the mold during the casting operation.

It is also an object of the invention to provide a casting machine which is relatively simple to operate, inexpensive to manufacture and devoid of complicated parts and movements.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a side elevational view of a casting machine embodying the improvements of this invention.

Fig. 2 is a view similar to Fig. 1 showing the parts in a position during which time a casting is being made.

Fig. 3 is a top plan view of the machine with the parts, substantially, in the position of Fig. 2.

Fig. 4 is a vertical sectional view through the machine taken on line 4—4 on Fig. 1.

Fig. 5 is a fragmentary sectional view showing

some of the parts in elevation and taken on line 5—5 on Fig. 1.

Fig. 6 is an enlarged fragmentary view of certain parts of Fig. 4 showing the construction of the pressure and sealing plates.

Throughout the several views of the drawings similar reference characters are employed to denote the same or similar parts.

As was noted above this invention pertains to a casting machine that is a machine in which air pressure is employed for forcing the molten metal into a mold. The machine will probably find its greatest uses in the dental field for making castings for replacement purposes in the mouth. The process of making replacement castings consists in making an impression of the part of the mouth to be replaced and then a wax pattern exact in all detail to the impression if the impression were not originally made in wax. This wax pattern or model is then suitably invested in an investment composition which constitutes the mold. The wax pattern or model is then dissipated by heat which results in a cavity having all of the detail of the wax pattern.

A finished mold is shown in broken lines in Fig. 4 and as there illustrated the reference numeral 10 indicates the cavity from which extends a sprue hole 11 which terminates at its upper end in a concave depression 12 forming the crucible for the metal to be melted and forced into the cavity. These parts were formed by investing the wax patterns thereof in a cementitious mass 13 which was allowed to stand and harden to form the mold. The cementitious mass was poured into a metallic cylinder generally referred to as a sleeve 14. It is this assembly that is placed on the casting machine to make the casting.

Referring now to the machine, it comprises a hollow casting 15 which constitutes the base for the machine and at the same time acts as an air pressure reservoir. Extending from the opposite sides of each end of the base 15 are lugs 16 which form the feet for the machine. Secured within the reservoir 15 is a pump cylinder 17 through which operates a pump piston 18 carried by the inner end of a piston rod 19. The piston rod 19 has secured to its outer end a knob 20 for actuating same and the rod is suitably packed as at 21 to prevent leakage. The other end of the base 15 has upstanding therefrom a hollow post 22 communicating with the reservoir in the base. Secured to the upper end of

the post 22 is an air gage 23 for indicating the pressure therein and in the reservoir.

The base-reservoir 15 illustrated in the drawings is substantially oval shaped in cross section, as illustrated in Fig. 4, and is therefore provided intermediate its ends with a flat portion 24 for the mold support. This mold support, as seen in Fig. 4, comprises a disc 25 having an aperture 26 at its center the base of which is formed as a conical seat 27. Surrounding the bore 26 and depending from the disc 25 is a circular boss 28 received in one end of a coil spring 29. In alignment with the disc boss 28 is a boss 30 upstanding from the seat 24 disposed within the other end of the coil spring 29. Projecting through the aperture in the boss 28 of disc 25 is a bolt having its threaded end 31 screwed into a threaded socket in the boss 30 and with its head 32 in the disc aperture 26. The bolt between its head 32 and threaded portions 31 is provided with a tapered shoulder 33 which rests on the tapered base 27 of the bore 26.

The bolt is sufficiently screwed into its socket to hold the disc 25 in position with the spring 29 under slight compression. As will be later pointed out, pressure on the disc 25 will permit it to deflect in the direction of said pressure and thereby permit the said disc 25 to take a position other than parallel with the base and at an angle thereto.

Mounted on the disc 25 is a collar 34 which will vary in thickness depending upon the height of the ring 14 in order to bring the top of said ring to a normal height for contact by the sealing plate.

Below the disc 25 is located the arms 35 and 36 of the forked end 37 of a lever 38. The lever 38 is provided on its other end with a flat tail 39. Intermediate its ends the lever 38 is pivoted at 40 between a pair of brackets 41 secured to the upper surface of the base 15 behind its seat 24.

The fork lever 38 normally takes the position illustrated in Fig. 1 with the ends of the arms 35 and 36 contacting the undersurface of the disc 25. The tail 39 of the lever is at this time contacting the adjustable button 42 on valve stem 43 of air valve 44. The stem 43 is spring biased to hold the button 42 and lever 38 in the position above described and clearly illustrated in Fig. 1. The valve 44 is threaded into the front face of the column and controls the flow of air therefrom and from the reservoir 15.

The upper end of the column 22 is narrowed in width as at 45 and received the arms 46 and 47 of the forked end 48 of operating lever 49. The column portion 45 and arms 46 and 47 are respectively provided with an aperture in axial alignment with one another through which passes pivot bolt 50 whereby the lever 49 is operable toward and from the base 15. The operating lever 49 is provided intermediate its length with an enlarged boss-like portion 51 in which is mounted the mold pressure and seal plates.

Referring to Fig. 4 it will be noted that the boss 51 of the lever 49 is provided therethrough with an aperture 52 the upper end of which is flared to provide a seat 53. The lower end of the aperture 52 communicates with a counter-bore 54 let into the boss from the lower surface thereof and which counter-bore is provided with a seat 55 at its base.

The aperture 52 of the boss 51 has extending therethrough a tube 56 which is provided at its upper end with an enlarged collar-like portion

57. Connecting the collar 57 with the tube 56 is a conical portion 58 which rests on the lever boss seat 53. The lower end of the tube 56 is threaded to receive a lock nut 59 which lock nut 5 also forms one abutment for a coil spring 60 which encircles the tube 56 and abuts on its other end with the counter-bore seat 55.

The tube 56, below the lock nut 59, has threaded thereon a disc 61 which may be referred to 10 as a pressure plate. The pressure plate 61 is cup shape and has projecting centrally thereof below the tube 56 a boss 62 which may be termed a distributing head. This boss 62 is solid except for a series of extremely small air holes 63 15 which effect communication between the tube 56 and atmosphere below the plate 61. In addition the boss or distributing head 62 has threaded centrally thereof a screw 64 which is employed by having its head more or less restrict 20 the flow through the small bores 63 and thereby regulate the air flow through the distributing head. The boss or distributing head 62 is externally threaded to receive a second cup shaped disc 65 which may be termed the sealing 25 plate. Pressed into the cup of the sealing plate 65 is a relatively soft material 66 preferably asbestos.

The upper end of the tube 56 is provided with a small hose coupling 67 to which is secured one 30 end of a piece of hose 68 which in turn has its other end connected to a hose coupling 69 projecting from the rear side of air valve 44.

Extending from the operating lever boss 51 is a lug 70 received between the arms 71 and 72 35 of the fork end 73 of a latch 74. The latch 74 terminates in a nose 75 which has a plane face 76 which is vertically disposed when the latch is in its operative position as will later be made clear. The latch face 76 cooperates with an abutment screw or bolt 77 threaded into an extension 40 78 at the top of post or column 22.

The operation of the mechanism is as follows:

The mold is prepared in the ring 14 as above described whereupon the ring is placed on the 45 collar 34 on the disc 25. It is to be understood that at this time the operating handle 49 is elevated to its inoperative position which is almost vertical of the base 15. At this time the pressure and sealing plates and other parts associated therewith have the angular position with respect to the operating handle 49 as illustrated in Fig. 1. At this time also the work, that is, mold support and parts associated therewith are in the angular position with respect to the base 50 15 as illustrated in Fig. 1. The pressure plate assembly and mold support assembly are respectively held in these normal positions by the 55 springs 60 and 29.

Metal in nugget form is placed in the crucible 60 12 and heat applied to melt same whereupon the operating handle 49 is moved to the position shown in Fig. 1 with the sealing plate lining 66 in contact with the corner of the ring 14. The operating lever is immediately continued in its movement downwardly toward the base 15 to the 65 position illustrated in Fig. 2.

During the movement of the operating handle 49 from the position of Fig. 1 to that of Fig. 2 the 70 springs 60 and 29 where compressed and the various assemblies rocked so that the upper surface of the ring 14 and under surface of the sealing material 66 were disposed in the same plane and in sealing contact with one another. As the mold assembly was depressed the disc 25 through the forked end 37 oscillates the lever 38

and through the lever tail 39 depresses the valve plunger for opening same and thereby permitting an air flow through the hose 68 to the tube 56 where the air is directed to the distributing head 62 of the pressure plate 61. The air passes through the distributing head aperture 63 to the crucible 12 forcing the molten metal therein through the sprue hole 11 to the cavity 10. When the handle or operating lever 49 reaches its final position the latch 74 drops by gravity about its pivot 79 in front of the abutment bolt 77 and retains the parts in this position. As soon as the casting operation is complete pressure is applied to the lever 49 to release the latch 74 whereupon its nose 75 is grasped for elevating the same and the pressure then released from the handle. The springs 29 and 60 immediately expand and return the parts to the positions illustrated in Fig. 1. The handle 49 is then manually raised to its uppermost position and the ring 14 with its embedded casting removed and processed in accordance with the usual custom.

From the foregoing it will now be seen that there has been provided a casting machine which will accomplish the objects initially set forth.

What is claimed is:

1. In a casting machine the combination of a base member, a mold supporting plate having a central recess therein and an aperture centrally of the recess, a bolt carried by the base extending through the support aperture and having a head disposed in the recess, and a spring around said bolt abutting on opposite ends with the supporting plate and base for causing the support to be elevated above the base and whereby pressure on the support will cause said support to be yieldably lowered toward the base.

2. In a casting machine the combination of a base member, a mold supporting plate having a central recess therein and an aperture centrally of the recess, a bolt carried by the base extending through the support aperture and having a head disposed in the recess, and a spring around said bolt abutting on opposite ends with the supporting plate and base for causing the support to be elevated above the base and whereby pressure on the support will cause said support to be yieldably lowered toward the base, said recess having the bottom thereof conically shaped and the bolt having the under surface of its head correspondingly conically shaped whereby a ball joint is provided between the supporting plate and bolt head to permit tilting of the support relative to the base.

3. In a casting machine the combination of a base member, a mold supporting plate having a central recess therein and an aperture centrally of the recess, a bolt carried by the base extending through the support aperture and having a head disposed in the recess, a spring around said bolt abutting on opposite ends with the supporting plate and base for causing the support to be elevated above the base and whereby pressure on the support will cause said support to be yieldably lowered toward the base, said base having pivotally mounted thereon a handle, means on said handle for engagement with and a covering for a mold on the supporting plate for supplying compressed air to the mold and including a yieldable spring whereby the mold engaging and covering means may be deflected with respect to the mold and handle while the said parts are being brought into operative relation,

and means for connecting a pressure source with the mold engaging and covering means.

4. In a casting machine the combination of a base member, a mold supporting plate having a central recess therein and an aperture centrally of the recess, a bolt carried by the base extending through the support aperture and having a head disposed in the recess, a spring around said bolt abutting on opposite ends with the supporting plate and base for causing the support to be elevated above the base and whereby pressure on the support will cause said support to be yieldably lowered toward the base, said base having pivotally mounted thereon a handle, means on said handle for engagement with and a covering for a mold on the supporting plate for supplying compressed air to the mold and including a yieldable spring whereby the mold engaging and covering means may be deflected with respect to the mold and handle while the said parts are being brought into operative relation, and means for connecting a pressure source with the mold engaging and covering means, said connecting means including a valve operable upon movement of the mold supporting plate after the mold and covering means have been brought into engagement with the mold.

5. In a casting machine the combination of a base member, a mold supporting plate having a central recess therein and an aperture centrally of the recess, a bolt carried by the base extending through the support aperture and having a head disposed in the recess, a spring around said bolt abutting on opposite ends with the supporting plate and base for causing the support to be elevated above the base and whereby pressure on the support will cause said support to be yieldably lowered toward the base, said base having pivotally mounted thereon a handle, means on said handle for engagement with and a covering for a mold on the supporting plate for supplying compressed air to the mold and including a yieldable spring whereby the mold engaging and covering means may be deflected with respect to the mold and handle while the said parts are being brought into operative relation, and means for connecting a pressure source with the mold engaging and covering means, said connecting means including a stationarily mounted valve, and a lever intermediately mounted on the base having one end contacting the valve and the other the supporting plate whereby movement of the support actuates the lever for opening the valve.

6. In a casting machine of the class described a mold covering and pressure supplying mechanism comprising an air tube, a handle having an aperture therein through which the air tube freely passes, a spring around said air tube and abutting on opposite ends with the handle and an abutment on the air tube for moving the air tube in one direction, a collar on the air tube limiting the movement thereof by the spring, a pressure plate threaded secured to the air tube below its spring abutment and said pressure plate having a threaded boss projecting therefrom, and a removable sealing member threaded on the pressure plate boss for engagement with the mold.

7. In a casting machine of the class described a mold covering and pressure supplying mechanism comprising an air tube, a handle having an aperture therein through which the air tube freely passes, a spring around said air tube and abutting on opposite ends with the handle and an abutment on the air tube for moving the air

tube in one direction, a collar on the air tube limiting the movement thereof by the spring, a pressure plate threadedly secured to the air tube below its spring abutment and said pressure plate having a threaded boss projecting therefrom, a removable sealing member threaded on the pressure plate boss for engagement with the mold, said sealing member being channeled on its under surface, and heat resisting sealing means packed in said channel for physical engagement with the mold.

8. In a casting machine of the class described a mold covering and pressure supplying mechanism comprising an air tube, a handle having an aperture therein through which the air tube freely passes, a spring around said air tube and abutting on opposite ends with the handle and an abutment on the air tube for moving the air tube in one direction, a collar on the air tube limiting the movement thereof by the spring, a pressure plate on the air tube below its spring abutment and said pressure plate having a threaded boss projecting therefrom, and a removable sealing member threaded on the pressure plate boss for engagement with the mold, said air tube collar having its under surface conically

shaped, and said handle having a correspondingly shaped seat around its aperture through which the tube passes whereby the sealing plate and pressure plate may be tilted universally with respect to the handle and whereby the air tube when urged to its normal free position by the spring will have its axis normal to the handle seat.

9. In a casting machine of the class described 10 a mold sealing assembly having in combination with an air tube, a pressure plate threadedly secured to the end of the air tube, an externally threaded boss depending from the pressure plate, and a removable sealing plate threaded on the pressure plate boss.

10. In a casting machine of the class described a mold sealing assembly having in combination with an air tube, a pressure plate threadedly secured to the end of the air tube, an externally threaded boss depending from the pressure plate, and a removable sealing plate threaded on the pressure plate boss, said sealing plate having its under surface channeled and said channel being packed with heat and flame resisting material for physical contact with the mold.

AUGUST L. WEYHING.
